UNITED STATES PATENT OFFICE.

GEORGE H. REIMER, OF FULTON, ILLINOIS, ASSIGNOR TO PATENT NOVELTY COMPANY, OF FULTON, ILLINOIS, A CORPORATION OF ILLINOIS.

DESIGN FOR A TOWEL-HOLDER.

49,622.

Specification for Design.

Patented Sept. 5, 1916.

Application filed January 31, 1916. Serial No. 75,446. Term of patent 7 years.

To all whom it may concern:

Be it known that I, GEORGE H. REIMER, a citizen of the United States, residing at Fulton, in the county of Whiteside and State of Illinois, have invented a new, original, and ornamental Design for Towel-Holders, of which the following is a specification, reference being had to the accompanying drawing, forming part thereof.

Figure 1 is a front elevation of a towel

holder, showing my new design, Fig. 2 is a side elevation of said towel holder.

I claim:

The new, original and ornamental design for a towel holder, as shown.

GEO. H. REIMER.

Witnesses:

CLARA F. STAPLETON,

THORA H. POPPE.
